UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Original application filed November 21, 1921, Serial No. 516,600. Divided and this application filed September 22, 1924. Serial No. 739,077.

To all whom it may concern:

Be it known that I, CHARLES DAVID BONSALL, a citizen of the United States, and a resident of the city of Pittsburgh, in the county of Allegheny and State of Pennsylvania, have invented a certain new and useful Improvement in Car Roofs, of which the following is a specification.

The matter hereinafter described and claimed is divided out of my pending application Serial Number 516,600, filed November 21, 1921, for patent for improvement in car roofs.

This invention relates principally to metal car roofs of the all-steel riveted-up type wherein self-supporting roof sheets extend from side plate to side plate and are formed along their side margins with lapping portions which are riveted together to form weather proofing joints or seams that function as carlines.

One of the principal objects of the present invention is to increase the strength and rigidity of the roof by improving the sectional shape and arrangement of the lapped portions of adjacent sheets. Another object is to enable the sheets to be pressed from a rectangular blank, thereby eliminating the expense of shearing the blank to special shape. Another object is to devise a box-girder seam whose upper half is formed by a strengthening rib of one sheet and whose lower half is formed by a strengthening rib of an adjacent sheet, thus permitting the use of strengthening ribs so shallow that they may be pressed in the sheets with relatively light power and small risk of rupturing the metal. Another object is to locate the box-girder seams partly above and partly below the plane of the body of the sheets, thereby obtaining a more uniform distribution of the metal in the roof and increasing the strength of the roof and reducing by one-half the height of the seams above the sheets. Another object is to secure effective ventilation of the car through the box joints. Another object is to utilize the box-joint as a drain channel for draining off water that may enter said joints, thereby permitting the use of fewer rivets and extreme care in driving the same. Another object is to re-

duce the weight of the roof, to simplify the construction thereof and to cheapen the cost of manufacture.

The invention consists principally in the construction hereinafter described; and it also consists in the combinations and arrangements of parts hereinafter described and claimed.

In the accompanying drawings, which form part of this specification and wherein like symbols refer to like parts wherever they occur,

Fig. 1 is a plan view of the end portion of a car roof embodying my invention, parts being shown broken away to more clearly illustrate the invention;

Fig. 2 is an enlarged transverse section through one half of the roof on the line 2—2 in Fig. 1;

Fig. 3 is a longitudinal section along the ridge line of the roof on the line 3—3 in Fig. 1;

Fig. 4 is a detail cross-section through one of the seams, the section being taken between the ridge and the eaves on the line 4—4 in Fig. 1;

Fig. 5 is a cross-section through one of the seams at the side plate, the section being taken on the line 5—5 in Fig. 1;

Fig. 6 is a cross-section through the ridge line of one of the roof sheets;

Fig. 7 is a plan view of a car roof embodying a modified form seam construction;

Fig. 8 is an enlarged transverse section through one half of said roof on the line 8—8 in Fig. 7;

Figs. 9, 10, and 11 are enlarged vertical cross-sections through one of the seams of the roof shown in Fig. 7, the sections being taken on the lines 9—9, 10—10, and 11—11, respectively, in Fig. 7;

Fig. 12 is a cross-section through one of the roof sheets for the roof shown in Fig. 7, the section being taken adjacent to the ridge line of said sheet; and

Fig. 13 is a cross-section through the eaves portion of the roof shown in Fig. 7, the section being taken through one of the seams on the line 13—13 in Fig. 7.

The roof shown in sheet 1 of the accompanying drawings comprises transversely

arranged load-sustaining roof sheets 15, which extend from eaves to eaves of the car. The roof sheets are supported at their eaves ends on the outwardly projecting uppermost flanges of the angle-bar side plates 16; and the eaves ends of said sheets are provided with down-turned eaves flanges 17 which overhang the outer edges of the top flanges of said side plates.

10 The roof sheets have hollow strengthening ribs 18 and 19 formed therein adjacent to their respective side margins, the rib 18 at one side margin of a sheet being pressed upwardly and the rib 19 at the opposite side margin of said sheet being pressed downwardly. This pressing of the ribs 18 and 19 in opposite directions with respect to the body of the sheet forms reverse strengthening ribs, one opening upwardly and the other opening downwardly.

15 The sheets are assembled bylapping their side marginal portions; that is, the downwardly opening rib 18 at one side margin of a sheet is placed over the upwardly opening rib 19 at the other side margin of an adjacent sheet; and the lapped portions of the sheets are secured together on opposite sides of the reverse ribs 18 and 19 by rows of rivets 20, whereby said reverse ribs cooperate 20 to form box-girder seams or joints 21, which constitute carlines. The rows of rivets on the one side of a box-girder joint 21 extend through the overlapping side margin 22 of one sheet and the adjacent underlying body portion of the other sheet; and the row of rivets on the opposite side of said joint extend through the overhanging body portion of said first mentioned sheet and the underlying side margin 23 of said second mentioned sheet.

25 The ribs 18 and 19 are preferably of channel section and gradually decrease in height and depth, respectively, from the ridge towards the eaves where they merge into the plane of the body of the sheets. The upwardly opening ribs or channels 19 merge into the body of the sheet at the inner faces of the side plates. The downwardly opening ribs or channels 18 merge into the body 30 of the sheet at the point where the eaves ends of the sheets are turned down to form the depending eaves flanges 17.

35 The sheets are pressed from blanks of uniform width and, therefore, the gradual decreased height of the channels 18 and 19 from the ridge toward the eaves results in a corresponding increase in the width of the sheets towards the eaves. This surplus metal is utilized in securing a uniform widening 40 of the channels 18 and 19 from the ridge towards the eaves with the result that the flanges 22 and 23 at the side margins of the sheets are of uniform width from eaves to eaves thereof.

45 65 By reason of the sheets being pressed

from a rectangular blank, the decreased height of the ribs 18 and 19 from the ridge towards the eaves enables the width of said ribs to be increased from the ridge towards the eaves. This arrangement increases the sheet lap as well as the seam lap and produces a box-girder seam construction of high and narrow section at the ridge, that is well adapted to withstand the vertical roof loads, and of broad flat section at the eaves that functions as a gusset to withstand the horizontal stresses.

70 Running boards 24 are arranged lengthwise of the car at the ridge and are securely bolted to the uppermost lateral flange of 75 Z-shaped running board saddles 25, whose lowermost lateral flanges rest on the roof sheets and are secured thereto by the rivets that secure the overlapping side marginal flange 22 of one sheet to the underlying 80 body portion of an adjacent sheet.

85 End sheets 26 are provided for each end of the car. The outer side marginal portions of the end sheets are supported on the uppermost flanges of angle-bar end plates 90 27 and are formed with depending flanges which overhang the outer margins of supporting flanges of said end plates. The end sheets are made in rights and lefts; that is, one of said end sheets is provided at its inner side margin with an upwardly opening 95 channel 19 and the other of said sheets is provided at its inner side margin with a downwardly opening channel 18.

100 In the modification shown in Sheet 2 of the drawings, the sheets 15^a are provided adjacent to one side margin with an upwardly open channel 19^a, which merges into the plane of the sheet near the inner face of the side plates, and are provided adjacent 105 to the other side margin with a downwardly open channel 18^a, which is turned down at 18^b over the eaves of the car and is open at its bottom. Thus, when the downwardly opening rib of one sheet is secured to the 110 upwardly open rib of an adjacent sheet, they form a box-girder seam 21^a whose ends are open.

115 The flanges 23^a located outside of the upwardly opening channels 19^a have depressed portions 23^b adapted to cooperate with the body portions of adjacent sheets to form 120 openings 28 in the box-girders 21^a formed by the lapped ribs 18^a and 19^a. These openings 28 establish communication between the 125 interior of the car and the interior of the box-girders 21^a, thereby permitting said box-girders to function as passageways or flues which serve to ventilate the car. These flues or passageways serve also as drain 130 channels for carrying off any water that may enter the joints of the box-girders, thus eliminating the necessity for a tight joint and reducing the number of rivets required for securing the lapped ribs 18^a and 135

19^a without affecting the water proofing qualities of the roof.

The invention is not restricted to the precise shapes and arrangements of parts shown in the drawings.

5 What I claim is:

1. A car roof comprising side plates a plurality of pitched metal roof sheets extending from side plate to side plate and 10 having their side margins overlapped horizontally at the level of the body portions, said roof sheets having reverse hollow ribs formed in their overlapped portions that are rigidly secured together to form hollow 15 girders.

2. A car roof comprising side plates a plurality of pitched metal roof sheets extending from side plate to side plate with their side marginslapping each other and 20 rigidly secured together along two lines at the level of the body portions of the sheets, the portions of the lower sheet between said lines being formed into a flat-bottomed channel, and the portion of the upper sheet between 25 said lines being formed into a flat-topped inverted channel.

3. A car roof comprising a plurality of metal roof sheets extending from eaves to eaves and having their side margins overlapped, said roof sheets having reverse hollow ribs formed in their overlapped portions that are rigidly secured together to 30 form hollow girders.

4. A car roof comprising a plurality of metal roof sheets extending from eaves to eaves and having their side margins overlapped horizontally at the level of the body portions of the sheets, said roof sheets having reverse hollow flat-topped ribs formed 35 in their overlapped portions that cooperate to form box girder seams, and means for rigidly securing together the lapped margins of the roof sheets on opposite sides of said 40 seams.

45 5. A car roof comprising a plurality of metal roof sheets extending from eaves to eaves and having their side margins overlapped and rigidly secured together, said roof sheets having reverse hollow strengthening ribs formed in their overlapped margins which increase in width and decrease in 50 depth from the ridge towards the eaves and are rigidly secured together to form hollow girders of increasing width and decreasing 55 depth from the ridge towards the eaves, the lowermost ribs of a girder merging into the body of the sheet adjacent to the eaves and the uppermost rib of said girder being open at the eaves, whereby said girder constitutes a drain channel for carrying off water 60 that enters said girder through the joints

between the lapped margins of said roof sheet.

6. A car roof comprising a plurality of metal roof sheets extending from side plate 65 to side plate with their side margins overlapped and rigidly secured together flush with the body portions of said sheets, the lapped margins being shaped to form hollow girders whose top and bottom walls 70 are disposed above and below the plane of the body of the sheets.

7. A car roof comprising a plurality of metal roof sheets extending from side plate to side plate with their side margins overlapped and rigidly secured together, the lapped margins being shaped to form box seams whose top and bottom walls are disposed above and below the plane of the body of the sheets, said box seams increasing 80 in width from the ridge towards the eaves.

8. A car roof comprising a plurality of metal roof sheets extending from side plate to side plate with their side margins overlapped and rigidly secured together, the lapped margins being shaped to form hollow girders whose top and bottom walls are disposed above and below the plane of the body of the sheets, said girders having openings 90 therein located below the body of the sheets and adapted to establish communication between the interior of the car and the atmosphere through said girder.

9. In a metal car roof, a plurality of roof sheets extending from side to side, each sheet having one edge overlapping the edge of the adjacent sheet and parallel ribs in each sheet extending from opposite sides of the sheet, means for securing the overlapped portions of the sheets together with the opposite extending ribs one above the other in register, and means for securing the ends of the sheets to side plates of the car, said registering ribs forming an air passage from 95 side to side of the car and means provided in said ribs forming a communication between said air passage and the interior of the car.

10. In a metal car roof, a plurality of roof sheets extending from side to side, each sheet having one edge overlapping the edge of the adjacent sheet and parallel ribs in each sheet extending from opposite sides of the sheet, the ribs on the upper side of the overlap extending upward and the ribs on 110 the underside extending downward, the ribs on the underside provided with apertures opening into the interior of the car.

Signed at St. Louis, Missouri, this 19th day of September, 1924.

CHARLES DAVID BONSALL.
